UNITED STATES PATENT OFFICE.

FLORENCE E. BEAGLE, OF ARLINGTON, OHIO.

IRONING-BOARD.

1,204,641.

Specification of Letters Patent. Patented Nov. 14, 1916.

Application filed April 20, 1916. Serial No. 92,503.

To all whom it may concern:

Be it known that I, FLORENCE E. BEAGLE, a citizen of the United States, residing at Arlington, in the county of Hancock and 5 State of Ohio, have invented certain new and useful Improvements in Ironing-Boards, of which the following is a specification, reference being had to the accompanying drawings.

10 This invention relates to certain improvements in ironing boards and has relation more particularly to a device of this general character whereby the board is adapted to be adjusted into operative or inoperative position, and it is an object of the invention to provide a novel and improved device of this general character whereby the board may be swung within a case or cabinet secured to a wall or other support so 20 as to have the board entirely out of the way when not required in use.

Furthermore it is an object of the invention to provide a device of this general character having novel and improved means 25 whereby the board may be effectively maintained in operative or horizontal position and whereby it may be easily released from said position and swung into an inoperative or substantially vertical position when not 30 required for use.

The invention consists in the details of construction and in the combination and arrangement of the several parts of my improved ironing board whereby certain important advantages are attained and the device is rendered simpler, less expensive and otherwise more convenient and advantageous for use, all as will be hereinafter 35 more fully set forth.

40 The novel features of the invention will hereinafter be definitely claimed.

In order that my invention may be the better understood, I will now proceed to describe the same with reference to the accompanying drawings, wherein—

Figure 1 is a view in elevation of an ironing board arranged in accordance with an embodiment of my invention with the parts in folded position; Fig. 2 is a sectional view taken substantially on the line 2—2 of Fig. 1, looking in the direction of the arrow; Fig. 3 is a sectional view taken substantially on the line 3—3 of Fig. 1; Fig. 4 is an elevational view showing the device adjusted into operative position; Fig. 5 is a fragmentary front eleva-

tional view with the board proper and the coacting struts omitted; Fig. 6 is a fragmentary view in top plan of the rear end portion of the board proper; Fig. 7 is a 60 fragmentary view in elevation of one of the bars as herein employed; Fig. 8 is a fragmentary view partly in elevation and partly in section illustrating a further embodiment of my invention; Fig. 9 is a fragmentary view partly in elevation and partly 65 in section illustrating a connection between the rear end portion of the board proper and the supporting frame coacting therewith; Fig. 10 is a view in rear elevation of 70 the supporting frame for the rear end portion of the board proper; and Fig. 11 is a view in top plan of the rear end portion of the board proper.

As disclosed in the accompanying drawings, C denotes a case or cabinet which may be secured, in suspended or elevated position, to the side of a wall or other support and which embodies the two vertically disposed sides 1, the top 2, the bottom 3 and 80 the back 4.

Interposed between and operatively engaged with the inner faces of the sides 1 and the back 4 at a predetermined point intermediate the top 2 and the bottom 3, are 85 the brackets 5 arranged in horizontal alignment and having the intermediate portions 6 offset inwardly relative to the sides 1.

Pivots engaged with the offset portions 6 are the angle bars 7 of predetermined 90 length and connected by the brace bars 8 preferably arranged in X formation, whereby the bars 7 will be caused to move in unison and in the same general direction. The outer extremities of the bars 7 are offset, as 95 at 9, and projecting laterally and outwardly from said offset portions 9 are the pins 10 disposed through the longitudinally disposed slots 11 formed in the upper ends of the bars 12 pivotally engaged, as at 14, 100 with the supporting struts 15.

The lower ends of the struts 15 are hingedly connected as at 16 with the bottom 3 of the case or cabinet C, while the upper ends thereof are tied or connected with a 105 transverse member 17. Suitably secured to the transverse member 17 is the double hinge 18 which is also secured to the under surface of the board B.

The board B is of suitable configuration 110 in plan and has its inner end portion provided with the plates 19 extending beyond

the longitudinal edges thereof, the extended portions of the plates 19 being provided with the forwardly directed arms or fingers 20 arranged on a suitable incline and partially intersecting the sides of the board B.

Extending between each of the arms or fingers 20 and the adjacent longitudinal edge of the board B is a bar 21 having its lower end pivotally engaged, as at 22, with the bottom 3 of the case or cabinet C and having its opposite end portion provided with the elongated longitudinally disposed slot 23 through which passes the pin 24 extending inwardly of a bar 7 at a point inwardly of but in close proximity to the offset portion 9 thereof.

Each of the bars 21 adjacent its upper end has its rear edge provided with a notch or recess 25 with which the extended portion of a plate 19 coacts to maintain the rear end of the board B in operative or horizontal position, it being self-evident that the struts 15 hereinbefore referred to serve to maintain the forward or outer end of the board B in operative position.

When it is desired to position the board B within the case or cabinet C, it is only necessary to elevate the rear end of the board to disengage the plates 19 from the notches 25 produced in the bars 21 and then cause the rear end portion of the board to slide downwardly upon the bars 21 until the board B is disposed substantially parallel with the struts 15, whereupon the board B together with the struts 15 may be readily swung upwardly into the cabinet or case C.

A conventional retaining means as indicated at 26 may be employed for maintaining the struts 15 together with the board B within the case or cabinet C. As any retaining means may be employed which will operate with convenience, a detail description and illustration thereof is thought to be unnecessary.

In the form of invention illustrated in Figs. 8 to 11 inclusive the struts 15^a are operatively connected with the sides 1^a of the case or cabinet C' through the medium of the pivotally connected brace rods 27 serving to limit the downward movement of the struts 15^a.

Hingedly connected with the bottom 3^a of the case or cabinet C' is a frame 28 herein disclosed as substantially X-shape in form and having its upper or outer end provided with the cross member 29 provided with the hook plates 30 adapted to interlock with the hook plates 31 carried by the rear end of the board B', whereby the rear end of the board is effectively supported in operative position. In order to hold the board B' against lateral movement, I find it of advantage to provide the free ends of the hook plates 30 with the recesses 32 adapted to receive the plates 31 hereinbefore referred to

and coacting therewith in a manner which is believed to be clearly obvious to prevent lateral movement of the board B'.

33 denotes a strip of flexible material preferably webbing having its inner end secured to the back 4^a of the case or cabinet C through the medium of the strip 34 extending transversely and entirely across the cabinet or case C', while the opposite end of the strip 33 is secured to the cross member 29. It will be self-evident that the strip 33 serves to limit the outward or downward movement of the member 29 yet permits a ready movement of said member within the case or cabinet C'.

The remaining features of the invention as disclosed in these figures is substantially the same as has been described relative to Figs. 1 to 7 inclusive.

From the foregoing description, it is thought to be obvious that an ironing board constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. A device of the character described including a cabinet provided with vertically disposed sides, a strut hingedly engaged with the cabinet and movable vertically, pivoted brace rods interposed between the cabinet and the strut, a board, a double hinge connection between the board and the outer end of the strut, and a member pivotally engaged with the cabinet and detachably engaged with the rear portion of the board for supporting the rear portion of the board in operative position.

2. A device of the character described including a cabinet provided with vertically disposed sides, a strut hingedly engaged with the cabinet and movable vertically, pivoted brace rods interposed between the cabinet and the strut, a board, a double hinge connection between the board and the outer end of the strut, and a member pivotally engaged with the cabinet and operatively connected in a detachable manner with the rear portion of the board for supporting the rear portion of the board in operative position.

3. A device of the character described including a cabinet provided with vertically disposed sides, a strut hingedly engaged with the cabinet and movable vertically, pivoted brace rods interposed between the cabinet

net and the strut, a board, a double hinge connection between the board and the outer end of the strut, and movable means carried by the cabinet coacting with the rear end of

5 the board for supporting the rear end of the board.

4. A device of the character described embodying a cabinet provided with vertical sides, a strut hingedly connected with the cabinet, a bar pivotally engaged with the cabinet and provided with a lateral extension adjacent its outer end, a second bar pivotally engaged with the strut and provided with a slot through which the extension of the first named bar is directed, a board operatively engaged with the outer end of the strut, and movable means carried by the cabinet coacting with the rear end of the board for supporting the rear end of the board.

20 5. A device of the character described embodying a cabinet provided with vertical sides, a strut hingedly connected with the cabinet, a bar pivotally engaged with the cabinet and provided with a lateral extension
25 adjacent its outer end, a second bar pivotally engaged with the strut and provided with a slot through which the extension of the first named bar is directed, a board operatively engaged with the outer end of the strut,
30 an elongated member pivotally supported by the cabinet at a point below the first named bar, the outer end of said member being provided with an elongated slot, a lateral extension carried by the first named bar disposed through the slot of the member, and
35

means carried by the rear end of the board coacting with the member for maintaining the rear end of the board in operative position.

6. A device of the character described embodying a cabinet provided with vertical sides, a strut hingedly connected with the cabinet, a bar pivotally engaged with the cabinet and provided with a lateral extension adjacent its outer end, a second bar pivotally engaged with the strut and provided with a slot through which the extension of the first named bar is directed, a board operatively engaged with the outer end of the strut, an elongated member pivotally supported by the cabinet at a point below the first named bar, the outer end of said member being provided with an elongated slot, a lateral extension carried by the first named bar disposed through the slot of the member, a plate carried by the board and extending beyond the longitudinal margin thereof, and an inwardly directed finger carried by the extension, said member being disposed between the finger and the adjacent edge of the board, said member being provided with a notch to receive the extended portion of the plate.

In testimony whereof I hereunto affix my signature in the presence of two witnesses.

FLORENCE E. BEAGLE.
